UNITED STATES PATENT OFFICE.

GEORGE F. SALISBURY, OF MINNEAPOLIS, MINNESOTA.

COMBINED AWNING AND SHADE.

Application filed November 22, 1921. Serial No. 516,953.

To all whom it may concern:

Be it known that I, GEORGE F. SALISBURY, a citizen of the United States, residing at Minneapolis, in the county of Hennepin and State of Minnesota, have invented new and useful Improvements in Combined Awnings and Shades, of which the following is a specification.

This invention relates to a combined awning and shade for windows and the like, the general object of the invention being to provide means whereby a curtain, hung on the outside of a window or porch opening, can be operated entirely from the inside and can be pulled partly down over the window and at an angle thereto to form an awning, or can be pulled entirely over the window in a position parallel therewith to entirely close the window and thus form a protection from sun, rain and wind.

Another object of the invention is to place the curtain on a roller automatically operated by a spring, a weight, or other mechanical means so that it will normally remain in rolled up condition.

This invention also consists in certain other features of construction and in the combination and arrangement of the several parts, to be hereinafter fully described, illustrated in the accompanying drawings, and specifically pointed out in the appended claim.

In describing my invention in detail, reference will be had to the accompanying drawings wherein like characters denote like or corresponding parts throughout the several views, and in which:—

Figure 1 is a front view showing the invention applied to a window.

Figure 2 is a sectional view.

Figure 3 is a detail view of the bracket member.

In these views 1 indicates a window and 2 indicates a spring roller, such as is used for window shades, which is supported in brackets 3 at the top of the window. Brackets 4 are secured to the outside of the window frame intermediate the ends thereof and a U-shaped member 5 has its extremities pivotally supported by said brackets. The bight of this member extends across the top of the window when said member is in raised position and the end of the shade or curtain 6, which is wound upon the roller, is secured to this bight. A substantially V-shaped

member 7 has its ends supported by the brackets 4 and the apex of this member is provided with a recess 8. A cable or cord 9 has one end secured to the recessed part 8 of member 7 and another part connected 60 with the bight of member 5 and then the cable passes downwardly through recess 8 and around a pulley 10 at the bottom of the window and through an opening in the frame of the screen 11 of the window to the 65 inside of same. When the cable is slack the spring roller will wind up the shade thereon and the member 5 will be in raised position. Member 7 will extend at right angles in front of the window so that the cable will 70 be thrown away from the window. Thus when the cable is pulled upon, the member 7 acts as a fulcrum for moving the member 5 upon its pivots and thus drawing the shade outwardly and downwardly at an 75 angle to make the shade act as an awning. By fastening the loose end of the cable in any desired manner the shade can be held in adjusted position. By pulling the shade all the way down the member 5 will 80 be moved against the lower half of the window so that the shade will entirely cover the window. It will thus be seen that the device can be used as an awning to partly shade the window or as a shade to entirely 85 cover the window.

While the drawing shows a spring roller it will of course be understood that any kind of an automatically operated roller can be used. For instance, the roller can be operated by a weight or the like.

Attention is called to the fact that the awning is operated entirely from the inside of the window so that it is not necessary to lean out of the window to raise and lower 95 the awning.

It is thought from the foregoing description that the advantages and novel features of my invention will be readily apparent.

I desire it to be understood that I may 100 make changes in the construction and in the combination and arrangement of the several parts, provided that such changes fall within the scope of the appended claim.

What I claim is:

A combined awning and shade of the character described comprising an automatically operated roller, a curtain thereon, stationary brackets, a U-shaped member having its ends pivotally secured to the brackets and the 110

2
bight thereof secured to the free end of the curtain, a substantially V-shaped member having its ends pivotally secured to the brackets, a cable having one end secured to a recess formed in the apex of the V-shaped member, thence secured to the bight of the U-shaped member then trained back through

the recess and being adapted to draw the U-shaped member downwardly to a horizontal position to make the curtain act as an awning or further downward to make the curtain act as a shade. 10

In testimony whereof I affix my signature.
GEORGE F. SALISBURY.
